UNITED STATES PATENT OFFICE.

JAFEW S. VAN BUREN, OF ALBANY, NEW YORK.

OVEN-DOOR.

1,170,858.

Specification of Letters Patent.

Patented Feb. 8, 1916.

Application filed July 8, 1915. Serial No. 38,705.

To all whom it may concern:

Be it known that I, JAFEW S. VAN BUREN, a citizen of the United States, residing at Albany, in the county of Albany and State of New York, have invented certain new and useful Improvements in Oven-Doors; and I do declare the following to be a full, clear, and exact description of the invention, such as will enable others skilled in the art to 10 which it appertains to make and use the same.

My invention relates broadly to improvements in stoves, and more particularly to oven doors for cooking stoves.

15 The object of the invention is to provide a door of this class with a hinged lining which may be opened when it is necessary to gain access to the inside of the door for any reason, but which when closed, constitutes 20 a shelf for the support of pans or the like drawn outwardly from the oven when the door is swung downwardly.

With this object in view, the invention resides in certain novel features of construction and combination hereinafter described 25 and claimed. In describing the invention, I shall refer to the accompanying drawings wherein like reference characters designate corresponding parts throughout the several 30 views and wherein:

Figure 1 is an inner side view of an oven door constructed in accordance with my invention, the lining plate being closed; Fig. 2 is a similar view with said lining plate 35 opened; Fig. 3 is a vertical section as seen along the plane indicated by the line 3—3 of Fig. 1; the door being shown in closed position; Fig. 4 is a similar view with the door in open position, and indicating the lining plate opened in dotted lines; Fig. 5 40 is a vertical section as seen on the plane indicated by the line 5—5 of Fig. 4; Fig. 6 is a perspective view of one corner of the door; and, Fig. 7 is a similar view of one of 45 the hinge members.

In these drawings which constitute a part of the application, the dotted lines O indicate the oven of a cook stove which is provided with the door D wherein resides the 50 gist of the present invention.

The door D comprises a normally upright front plate 1 of rectangular or other preferred formation, provided on its surrounding edge with a flange 2 extending rearwardly toward the oven O, the lower portion 55 of this flange being shown in the present

embodiment of the invention as provided with hinge studs 3 adapted for co-action with eyes or the like carried by the stove and designated by the dotted lines E. On 60 the inner side of the plate 1, at the intermediate portion thereof, is a C-shaped flange 4 which surrounds the thermometer and to which said thermometer is secured by stove bolts or the like 6. Directly beneath 65 the thermometer 5, and disposed slidably upon the inner side of the front plate 1, is an appropriate type of damper 7 having an operating handle 8 disposed in front of said plate. One or more stove bolts 9 slidably 70 secure the damper 7 in position upon the plate 1, whereby said damper may be removed when necessary for repairing or the like.

When the door D is swung downwardly to 75 the position shown in Fig. 4, the edge of the flange 2 is adapted to be disposed in line with the bottom of the oven O, thus allowing pans and the like removed from the oven to be supported upon the door. Heretofore, 80 it has been the common practice to so secure a lining plate to the door as to allow this plate to receive the utensils removed from the oven. This construction has been found to operate to advantage until repairing of the damper or thermometer is necessary or until the interior parts of the door D need cleaning. It is then of course necessary to remove the lining plate, but the bolts or the like securing the same in place have 85 usually become so rusted as to prevent this from being readily accomplished. It therefore becomes highly expedient to provide simple and efficient means whereby the lining plate will remain in closed position under ordinary circumstances, and whereby it may be readily swung outwardly when desired for gaining access to the inner side of the door proper for the purposes above suggested. To this end, the lining plate 10 is 90 provided, such lining being surrounded by the flange 2, disposed flush with the edge thereof, and hinged at its upper edge thereto. The plate 10 may be of any preferred formation, but it is preferably of openwork 95 design such as shown in the drawings, in which the plate in question is shown as having a solid central portion 10^a, a plurality of slats or the like 10^b formed integrally therewith and radiating therefrom, and appropriate ribs 10^c to which the intermediate portions of said slats are secured.

The ends of the slats 10^b rising from the central portion 10^a are shown as formed integrally with a hinge rod 11 which is disposed, directly beneath the upper portion of the flange 2 and which is confined in this position by L-shaped hinge members 12 having depending attaching feet 13 disposed in contact with and bolted at 14 to the upper portion of the plate 1. The upper ends of the feet 13 abut lugs 15 which are cast integrally with the upper edge portion of the aforesaid plate 1, while the sides and lower ends of said feet are inserted between trios of lugs 16 which are likewise formed integrally with and project inwardly from the plate 1. In addition to the lugs 15 and 16 for preventing movement of the members 12, the upper ends of the latter are preferably notched as at 17, said notches receiving ribs 18 which are formed on the lower side of the upper portion of the flange 2, by the unique disposition of parts above described, although the construction is very simple, and effective and inexpensive hinge is provided. It is to be observed that the lining plate 10 is hinged at its upper edge to the upper edge of the door D, whereas the lower edge of the latter is hinged to the oven O, this being essential since no means is necessary to retain the plate 10 in active position when the door D is closed.

In order to effectively support the plate 10 when the door is swung to the horizontal position shown in Fig. 4, a plurality of projections 19 is preferably formed on the inner side of the flange 2, said projections receiving thereon the plate 10 as clearly shown in several figures of the drawings. The projections in question may be of any desired shape, but they are preferably in the form of ribs extending transversely of the flange 2 whereby the same is reinforced thereby.

From the foregoing description, taken in connection with the accompanying drawings, it will be evident that although comparatively simple construction has been provided for carrying out the object of the invention, the complete door will be very efficient in operation and will possess a number of advantageous features.

In the drawings certain specific details of construction have been illustrated for producing probably the best results and in the preceding such details have been described, but it will be evident I need not be limited thereto otherwise than to the extent to which the appended claims restrict me.

I claim:

1. In combination, an oven door having

hinge means on its lower edge, and a lining 60 plate hinged to the rear side of said door at the upper edge thereof.

2. An oven door comprising a front plate having a rearwardly extending surrounding flange, a flat lining plate surrounded by the 65 rear edge portion of said flange and disposed flush with the rear edge thereof and means hingedly connecting the flange and the lining plate.

3. An oven door comprising a front plate 70 having a continuous flange extending rearwardly from its edge, a plurality of projections extending inwardly from said flange and spaced forwardly from the rear edge thereof, and a hinged lining plate surrounded by the rear edge portion of said flange, disposed flush with the edge thereof, and bearing on said projections.

4. An oven door comprising an upright front plate having a continuous flange extending rearwardly from its edge, a plurality of transverse ribs formed integrally with the inner side of said flange and terminating at points spaced forwardly from the rear edge thereof, and a hinged lining plate surrounded by the rear edge portion of said flange, disposed flush with the edge thereof, and bearing against the rear ends of said ribs.

5. An oven door comprising a front plate 90 having a continuous flange extending rearwardly from its edge, a lining plate surrounded by the rear edge portion of said flange and including a hinge bar disposed adjacent a portion of said flange, and L-shaped hinge members receiving in the angles thereof the hinge bar, and having attaching feet secured to the front plate.

6. An oven door comprising a front plate having a continuous flange extending rearwardly from its edge, a lining plate surrounded by the rear edge portion of said flange and including a hinge bar disposed adjacent a portion of said flange, L-shaped hinge members receiving in the angles thereof the hinge rod, attaching feet formed on said hinge members and secured to the front plate, and spaced lugs formed integrally with said front plate and abutting the edges of the feet.

In testimony whereof I have hereunto set my hand in presence of two subscribing witnesses.

JAFEW S. VAN BUREN.
